United States Patent Office

Des. 185,772
Patented July 28, 1959

185,772

PITCHER

Keith B. Mount, New Providence, N.J., and Clark D. Sims, Elmhurst, Ill., assignors to Lily-Tulip Cup Corporation, New York, N.Y., a corporation of Delaware

Application March 10, 1959, Serial No. 54,925

Term of patent 14 years

(Cl. D44—21)

Fig. 1 is a side elevational view of a pitcher embodying our new design;

Fig. 2 is a plan view of the pitcher shown in Fig. 1; and

Fig. 3 is a front elevational view of the pitcher shown in Figs. 1 and 2.

We claim:

The ornamental design for a pitcher, substantially as shown.
